UNITED STATES PATENT OFFICE

151,518

DESIGN FOR AN APRON

Marie J. Kraft, Three Oaks, Mich., assignor to
The Warren Featherbone Co., Three Oaks,
Mich., a corporation of Michigan

Application September 24, 1947, Serial No. 141,557

Term of patent 14 years

(Cl. D3—26)

To all whom it may concern:

Be it known that I, Marie J. Kraft, a citizen of the United States, residing at Three Oaks, Berrien County, Michigan, have invented a new, original, and ornamental Design for an Apron, of which the following is a specification, reference being had to the accompanying drawing, forming a part thereof.

I claim:

The ornamental design for an apron, substantially as shown.

MARIE J. KRAFT.
